UNITED STATES PATENT OFFICE.

BIRGER LJUNGSTRÖM, OF STOCKHOLM, SWEDEN, ASSIGNOR TO AKTIEBOLAGET SEPARATOR, OF STOCKHOLM, SWEDEN, A COMPANY.

CENTRIFUGAL MACHINE.

No. 891,845.

Specification of Letters Patent.

Patented June 30, 1908.

Application filed July 23, 1906. Serial No. 327,409.

To all whom it may concern:

Be it known that I, BIRGER LJUNGSTRÖM, of Fleminggatan 8, Stockholm, Sweden, engineer, a subject of the King of Sweden, have invented certain new and useful Improvements in Centrifugal Machines; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

In the hitherto known centrifugal machines for separating liquids from solid masses such as from salt- or sugar-crystals in order to bring the latter to a dry condition, a cylindrically or conically shaped drum 20 with perforated mantle has been used in which the material to be dried was introduced for separating purposes. The solid parts remain in the drum, but the liquid flows through the perforated mantle and is 25 caught in a suitable receptacle. With a centrifugal machine of this kind, a complete degree of separation cannot be obtained.

The present invention relates to such centrifugal machines which not only operate 30 without interruption, but are adapted for great separating efficiency.

While I have pointed out that the present invention relates to centrifugal machines such as I have just been speaking of, for the 35 purpose of making this clear I will repeat that the centrifugal machines of the present invention are used for the purpose of separating liquids from solid masses, such as from salt or sugar crystals, in order to bring the 40 latter to a dry condition.

The object of this invention is obtained by making the "drum" of conical plates, placed one above the other, and provided with perforations of suitable shape, there 45 being between two perforated plates a solid plate which forms a kind of guiding plate for the separated liquid. The surface on which separation takes place in such a machine is very large in proportion to the dimensions 50 of the drum and accordingly its separating power is very considerable.

The drawing illustrates in Figures 1 and 2 vertical sections through the drums of two examples of construction.

55 The conical separating plates *a* (as shown

in Fig. 1) are perforated like sieve bottoms. Their outer edges *b* are suitably bent down cylindrically at this point to narrow the slot between the plate *a* and the plate *c*, to be hereinafter described, thus partially stopping or arresting the material so that the solid parts may pass through the drum with such reduced speed as is necessary for drying to take place.

Between the sieve plates *a*, solid plates *c* 65 are arranged which serve for guiding the separated liquid to a suitable receptacle so as to prevent a remixing of the solid and liquid constituents. The solid constituents slide along the sieve plates and are slung out 70 over the edges *b* into a special receptacle, not shown in the drawing. The plates *a* and *c* are carried by the pillars 10, secured to disk 11, which is connected to shaft 12.

The described form of construction of the 75 centrifugal machine is suitable especially for such masses, the solid constituents of which are not too finely divided, *i. e.*, for sugar crystals, salt crystals, and the like. For porcelain-earth or other very fine solids, the 80 centrifugal machine illustrated in Fig. 2 is more suitable. In this the outflow-perforations are formed in the known manner between two parts, movable with regard to each other. The openings may, therefore, 85 be very finely adjusted without fear of their becoming constricted, for the solid particles which might possibly get into the openings are continually changing their position, and reach soon the edge and are flung out.

In Fig. 2, the conical separating plates *a* 90 are formed of rings, spaced apart to form grooves *d*. These rings are secured together and the plates thus formed are secured to the guide plates *c*, which are connected by bolts or pillars *e* to the disk *f*, the latter being connected with the hollow shaft *g*, so as to rotate therewith. In the grooves *d* of the plates *a* are rings *h*, which are carried by bolts or pillars *i* on a disk *k* on the shaft *l*. The two 100 shafts *g* and *l* are rotated, but at a differential speed, whereby the rings *h* and the plates *a* have a relative movement. The liquid flows through the slots and is led away by the guide plates *c*. The solid particles, however, 105 slide along the plates *a* and rings *h* and are collected at the cylindrical surfaces *m* by plates *n*, whence they may be guided away in suitable manner. Instead of arranging each guide-plate *c* in Fig. 1 loosely about a 110

sieve-plate *a*, both plates may be made integral and the liquid led outside through channels left between the plates.

Having now fully described my invention, 5 what I claim and desire to protect by Letters Patent is—

1. In a continuously operative centrifugal machine for separating liquids from solid constituents, in combination, an upper and

10 lower conically shaped plate, the upper plate having openings therethrough, said plates forming between them a separating chamber and a solid conical plate superposed upon said upper plate, all of said plates being rotatably mounted, whereby the liquids, separated from the solids and passing through the plate having openings, are caught by the solid plate and led to the periphery.

2. In a continuously operative centrifugal 20 machine for separating liquids from solid constituents, in combination, a series of upper and lower conically shaped plates, each pair of plates forming between them a separating chamber, the upper plate of each pair 25 having an opening, a solid conical plate, superposed above the plate, having openings of each pair of plates; all of said plates being rotatably mounted, whereby the liquids, separated from the solids in each chamber 30 and passing through the plates having openings, are caught by the solid plates and led to the periphery.

3. In a continuously operative centrifugal

machine for separating liquid from solid constituents, in combination, superposed alternate conically shaped separating plates, having openings therethrough and conically shaped solid guiding plates, each of the separating plates being secured to the guiding plate above it, both the guiding plates 40 and the separating plates being rotatably mounted.

4. In a continuously operative centrifugal machine for separating liquid from solid constituents, in combination, superposed alternate 45 conically shaped separating plates; having openings therethrough, devices in said openings, solid guiding plates, said devices in said openings having a relative movement with respect to the corresponding 50 separating plate.

5. In a continuously operative centrifugal machine for separating liquids from solids, a series of upper and lower plates, both of conical shape, the upper plates being perforated, 55 said plates being rotatably mounted, the space between said plates forming separating chambers of conical shape and opening outwards.

In testimony, that I claim the foregoing 60 as my invention, I have signed my name in presence of two subscribing witnesses.

BIRGER LJUNGSTRÖM.
